UNITED STATES PATENT OFFICE.

CLARENCE RICHARD BUSCHMEYER, OF DAYTON, OHIO, ASSIGNOR TO JOHN Q. SHERMAN
AND WILLIAM C. SHERMAN, BOTH OF DAYTON, OHIO.

ROTARY PUNCH.

1,333,704.

Specification of Letters Patent. Patented Mar. 16, 1920.

Application filed October 10, 1917. Serial No. 195,820.

To all whom it may concern:

Be it known that I, CLARENCE R. BUSCHMEYER, a citizen of the United States, and a resident of Dayton, in the county of Montgomery and State of Ohio, have invented certain new and useful Improvements in Rotary Punches, of which the following is a full, clear, and exact description, reference being had to the accompanying drawings, forming part of this specification.

The object of my invention is to provide a rotary punch for punching holes in paper, cardboard, sheet metal and the like in which the punching dies shall be so mounted and operated that there shall be no shearing cut as the punch is operated.

This object is attained by mounting the coöperating dies pivotally on the rotating member and by means of cams with which the dies are connected maintaining parallelism between the male and female members of the die punch between which the sheet to be treated is passed, so that the punch acts upon the sheet always at a right angle to the web or sheet under treatment and without any tendency to shear due to the rotary movement of the member upon which the dies are mounted.

While my improvement is adapted for the punching of holes in a web or sheet of any material, in the particular embodiment thereof to be hereinafter pointed out and claimed, I have designed a machine especially intended for punching a uniformly spaced continuous series of holes along the side edges of strips or webs of paper designed for use in autographic registers of the sprocket wheel feed type and in which my improved punch is intended to be attached to the printing press employed for printing the webs of paper and to be run continuously in connection with the printing operation.

In the drawings,

Figure 1 is a side elevation of my rotary punch.

Fig. 2 is a front elevation.

Fig. 3 is a cross section of the upper rotary member, considerably enlarged, on the line 3, 3, of Fig. 2.

Fig. 4 is a cross section on the line 4, 4, of Fig. 2.

Fig. 5 is a detail cross section showing in dotted lines the position of both crank arms for the die units.

Fig. 6 is a plan view in detail of the balancing shaft upon which the dies are mounted.

Fig. 7 is a detail of the web of paper showing the series of holes.

The punching mechanism is mounted in a substantial framework consisting of side standards 1, 1, top 2 and bottom 3, and when used in connection with a printing press the framework will be attached to the press in convenient position to receive the web of paper 4 which is supplied from the roll 5.

In connection with the use of such strips in autographic registers, it is usual to print and perforate the paper in a wide strip and afterward to slit the paper into the proper widths. In illustrating my invention, I have shown six sets of the punches for perforating the side edges of five strips of paper, the outside edges of the strip used being punched with a single series of holes and the intermediate portions punched with a double series as shown in Fig. 7, and the web afterward divided so as to form single strips with a single series of openings along each edge.

The construction and operation of the punching mechanism, however, of course is the same whether only a single series of holes are to be punched, or any number that may be desired.

Mounted horizontally in suitable journals in the side standards 1, 1, of the framework, one above the other, are the shafts 6, 7, 9, which carry the die units. As illustrated in the drawings, these die units are mounted on disks 8, 8, for the upper shaft, and 9, 9, for the lower shaft, which disks are secured to their respective shafts by set screws 24. The dies are tightly mounted on shafts 10, 10, journaled in the disks 8, 8, and 9, 9, near the periphery thereof. In the construction as illustrated in the drawings, these die units comprise the male die heads 12, 12, which are secured by set screws 13, 13, to their respective shafts. These heads carry the male cutting punches 14, 14, of which four are provided in the embodiment illustrated, spaced equal distances apart. These male dies coöperate with the female die plates 15, which are correspondingly mounted on their respective shafts 10, and held by set screws 16. Each of the shafts 10 (see Fig. 6) is provided at its end on the 110

outside of the disk plates with crank arms 17, 18, extending in opposite directions and carrying the studs 19, 20. These studs ride in cam grooves 21 in the face of the fixed 5 cams 22, 23. The cam grooves 21 are so formed that as the shafts 10 carrying the die units are rotated by the shafts 6 and 7, the action of the cam grooves will maintain 10 the die units in exact horizontal relation and prevent them from upsetting or tipping during the rotation, the shafts 10 oscillating to maintain this horizontal position of the dies. One of the shafts, as 7, when the attachment is to be used with the printing 15 press, is driven by the gear 25 keyed to the end thereof (see Fig. 1), and this gear is driven by the gear 26 from the printing machine drive. Of course other methods of driving the rotary punching devices may 20 be provided.

In order that there may be no lost motion in the driving of the upper die members, I prefer to drive the upper shaft 6 from the lower shaft through the medium of a slide 25 bar and link connection of the kind used in steam engines. The gear 25 carries a stud 27 which is coupled by a link 28 to a slide block 29, mounted to slide horizontally in a slide guide 30, secured to the framework, 30 and the slide block 29 is coupled by the link 31 to the crank arm 32 secured on the outer end of the shaft 6.

On the opposite side of the machine, the shaft 7 is provided with a crank arm which 35 is coupled by a link 33 with a corresponding slide block 34, mounted to slide horizontally in the slide guide 35, and the slide block is also coupled by the link 36 with the crank arm 37 mounted on the shaft 6. The slide 40 and link connections for the opposite ends of the two shafts 6 and 7 are set with the crank arms pivoted approximately forty-five degrees apart with reference to the axes of the shafts, or in other words, set on the 45 quarter, so that there is never any dead center and lost motion is thereby avoided, and the rotary members carrying the die units can be operated with great accuracy.

While I have not illustrated it in the 50 drawings, ball bearings will be provided for the various crank arms where wear is anticipated.

In the embodiment of my invention in which webs of paper for use in autographic 55 registers are to be perforated with holes along the side edges, it is essential that the holes shall be uniformly spaced. I have therefore provided four die punches and arranged the die units so that the punching 60 operations shall follow in succession and the distances between the holes shall be exactly uniform. With the construction illustrated, in order to obtain the series of holes as shown in Fig. 7, with four punches in each 65 unit, I provide eight of the units for each

rotary member, and these eight units are spaced forty-five degrees apart. Of course with three or two punches in each unit, a different spacing would have to be provided for the units.

The construction and operation of the machine will be obvious from the foregoing description. The web of paper 4 is run between the rotary members, and the shaft 7 driven in any suitable way, which in turn 75 as described drives the shaft 6, and the male and female die heads are brought together without any shearing cut by reason of the action of the cam grooves on the ends of the die unit shafts. Each of the male die units 80 is provided with a stripper plate 38, mounted on pins 39, 39, with coiled springs 40 to cause the plate to strip the paper from the punches as the male die leaves the female die.

It will of course be understood that as many sets of dies may be strung on the various shafts as desired, and that the die units may be so spaced as to punch the holes in any desired relation.

Having thus described my invention, what I claim as new and desire to secure by Letters Patent, is:

1. In a rotary punch, a pair of rotary members with coöperating male and female 95 dies pivotally mounted on said rotary members, and means to cause said dies to maintain parallel relation to each other as they are brought together with the rotation of the rotary members, and means for driving one 100 of said rotary members, with horizontal slide and link connection with the other rotary member whereby the rotary members may be driven in unison.

2. In a rotary punch, a pair of rotary 105 members with coöperating male and female dies pivotally mounted on said rotary members, and means to cause said dies to maintain parallel relation to each other as they are brought together with the rotation of the 110 rotary members, and means for driving one of said rotary members, with double horizontal slide and link connection with the other rotary member, said connections being set at different angles with relation to the 115 horizontal axes of the rotary member, for the purpose described.

3. In a rotary punch, a pair of shafts with disks secured thereon, die carrying shafts mounted on said disks at equal distances 120 from the axis of rotation of the main shafts, coöperating male and female dies secured on said die shafts, each die shaft provided with a crank arm, with a cam common to all die shafts carrying similar dies and having an annular slot therein eccentric to the main shafts, said cam adapted to receive the crank arms to enforce a constant horizontal position of the dies on the die shafts, and means for driving the main shafts simul- 130

taneously whereby the dies may be maintained in parallel relation as they are brought together.

4. In a rotary punch, a pair of shafts with 5 disks secured thereon, die carrying shafts mounted on said disks at equal distances from the axis of rotation of the main shafts, coöperating male and female dies secured on

said die shafts, each die shaft provided with a crank arm, with a cam common to all die 10 shafts carrying similar dies, and means for driving one of said main shafts, with horizontal slide and link connection with the other shaft whereby said shafts may be driven in unison.

CLARENCE RICHARD BUSCHMEYER.
